(57) **CLAIM**

The ornamental design for a gas combustor, as shown and described.

DESCRIPTION

FIG. 1 is a perspective view of a gas combustor showing the design;

FIG. 2 is a front side elevation view thereof;

FIG. 3 is a rear side elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view illustrating a rotated position thereof; and,

FIG. 9 is a perspective view illustrating another rotated position thereof.

The broken lines show portions of a gas combustor that form no part of the claimed design.
